UNITED STATES PATENT OFFICE

WAYNE P. ZENT, OF TROY, NEW YORK

AMUSEMENT DEVICE

Application filed June 27, 1929. Serial No. 374,261.

My invention relates to amusement devices and particularly to means for making an application of motive power and electrical energy to wheeled vehicles traveling upon a plane or planes, boats and the like upon water within an aquatic tank and airplanes and the like to be floated in the air from a power driven mast.

The object of this invention is to provide an amusement device that will be adapted to a plurality of objects operated by a single power and electrical source, both at a remote control.

A further object is to provide a uniform means of driving power and a source of electrical energy that is certain and safe in operation.

A further object is to provide means of operation of other objects and signals located in relation to but independent of the main objects and with interlocking means of power and electrical source and control.

A further object is to provide means whereby an assembly of several units may be added to the main structure or unit as desired.

A further object is to provide a uniform and simple semi-automatic connection of the objects to a power driving device and electrical connections with remote control.

With the above primary and other incidental objects in view, as will more fully appear in the specification, the invention consists of the features of construction, the parts and combinations thereof, and the mode of operation or their equivalents hereinafter described and set forth in the claims.

Referring to the drawings, Fig. 1 is a top plan view of the main device. Fig. 2 is a vertical section of same taken on line 2—2. Fig. 3 is a top plan view of same with top removed showing power rim, cams for operating side devices and other features. Fig. 4 is a bottom plan view of one of the corner plates. Fig. 5 is a broken away section of one corner of the main device showing terminal holes and other features. Fig. 6 is an enlarged vertical section showing fulcrum device to transfer power to the corner plate devices. Fig. 7 is a vertical section of same taken on the line 7—7. Fig. 8 is a bottom

plan view of the control panel showing bus connections of the control units. Fig. 9 is a top plan view of the center boss showing terminal studs. Fig. 10 is a bottom plan view of same showing bus connection of plural terminal studs. Fig. 11 is a view in side elevation of a fire engine representing one of the devices to be operated on and by the main device. Fig. 12 is a top plan view of same. Fig. 13 is a front end view of same. Fig. 14 is a rear end view of same emphasis being made of the sub-power device located on the vehicle. Fig. 15 is a bottom plan view of same. Fig. 16 is a view in side elevation of a vehicle to be operated on the main device by straddling the power driving rim and showing other means of sub-power to devices located on the vehicle. Fig. 17 is a top plan view of same. Fig. 18 is a rear end view of same. Fig. 19 is a front end view of same. Fig. 20 is a view in side elevation of a vehicle to be run on the outside plane of the main device and showing use of electric headlights and warning signal. Fig. 21 is a top plan view of same. Fig. 22 is a bottom plan view of same. Fig. 23 is a front end view of same accentuating the use of a single light for plural headlight reflection. Fig. 24 is a view in side elevation of an animated object to be run on the main device. Fig. 25 is a rear end view of same showing the means of animation. Fig. 26 is a top plan view of the right hand side of Fig. 24 showing the means of connection to the power rim of main device. Fig. 27 is a view in side elevation of a vehicle to be run on a grooved track on the main device. Fig. 28 is a bottom plan view of same showing use of plural wheel trucks and means for attaching same to power driving rim. Fig. 29 is a rear end view of same partly broken away. Fig. 30 is a view in side elevation of like device with single wheel truck and means for illumination. Fig. 31 is a top plan view partly broken away of same. Fig. 32 is a rear end view of same. Fig. 33 is a vertical section of Fig. 31 taken on the line 33—33. Fig. 34 is a view in side elevation of a locomotive with sub-power means on the vehicle to sound a warning signal. stressing the sub-power means. Fig. 36 is a front end view of same. Fig. 37 is a bottom plan view of same. Fig. 38 is a vertical section of Fig. 35 taken on the line 38-38. Fig. 39 is a view in side elevation of a wheeled boat showing means of intermittent electric contact. Fig. 40 is a top plan view of same. Fig. 41 is a rear end view of same. Fig. 42 is a vertical sectional view of an air beacon showing means for revolving and intermittent electric light contact. Fig. 43 is a bottom plan view of the contact structure. Fig. 44 is a horizontal section of Fig. 42 taken on the line 44-44. Fig. 45 is the same on the line 45-45. Fig. 46 is the same on the line 46-46. Fig. 47 is a top plan view of the air beacon showing ramp on power driving rim to engage with an electric contactor. Fig. 48 is a vertical section through the aquatic tank showing a floating light buoy. Fig. 49 is a top plan view of same. Fig. 50 is a view in perspective of a connector foot. Fig. 51 is a vertical sectional view of a lighthouse showing means for light and sound signals. Fig. 52 is a view in elevation of right hand side of Fig. 51. Fig. 53 is a top plan view of Fig. 51. Fig. 54 is a diagrammatical view showing the electrical wiring of the device illustrating how electrical connections are made through all switches and contact plates.

Like parts are indicated by similar characters of reference throughout the several views.

This invention comprises a series of units with suitable connections for assemblage into a single unit, the following being a description of each unit with an independent or collective explanation of operation:

Unit A, comprising a power unit, electric transformer unit, driving devices, electric control panel, aquatic tank, tracks or planes for vehicle travel, sections for mounting of electrical and mechanical devices, and a means of semi-automatic electrical connections, in which 1 is a box or frame of which 1a is the bottom, 1b the sides, 1c the outer arc of the top and 1d the inner arc of the top as determined by the slot 2. Pipe flange 3a and leveling bearings 4 mounted on 1a. Center pipe 5 mounted in 3 acting as a shaft for grooved loose pulley or power disc 6 mounted on friction bearings 7 in suitable runways in 3. Mounted on 6 is a circular plate 8 having a cup like rim 9 extending through the slot 2 said rim being associated with and driven by the power disc 6. The top 1c is mounted to the sides 1b. The top 1d has a pipe flange 3a for mounting on the pipe 5 and is provided with leveling bearings 4 and a boss 10 which provides means for positioning the aquatic tank 11 on the top of 1d. Tank 11 provided with a wave resisting flare 12 and a center opening 13 for the entering of the boss 10. Pulley 6

is driven by a three speed forward and reverse motor 14 through the belt 15.

The top 1c is provided with corner plates 16 for the mounting of signal and other devices and a corner plate 16a for motor and transformer unit and a control panel 19. The corner plates 16 are mounted on studs 17 in 1b and fastened by thumb nuts 18 which automatically complete electrical connections from the control panel 19 to the corner plates 16. In Fig. 4 is shown the buses for electrical connections on the corner plates 16, the terminal holes 20 engaging with the studs 17 in 1b and complete electrical connections to the studs 21 when thumb nuts 18 are seated. Thumb nuts 22 are used to position and electrically connect the signal and other devices used in conjunction with the corner plates 16. An intermittent electrical connection is provided in the stud 23 and its thumb nut 24.

A swiveled fulcrum drive device 25 is mounted by two set screws 26 to 1a partly beneath 16 and extending beneath 1b to engage with 9 and its cams 27 through the drive roller 28. A fulcrum arm 29 is swivel mounted on 25 at 30 and carries the roller 28 which is held against 9 or 27 by the spring 31. Fulcrum arm 29 is offset at 32 and carries a drive roller 33 and an alinement roller 34 which travels on plane of 25. When the rim 9 is driven by the motor 14 and the rim cams 27 engage with the roller 28 the fulcrum arm 29 swivels at 30 and carries the drive roller 33 on offset 32 to engage with the hinged plate 35 mounted on under side of corner plate 16 forcing it upward and holding it seated against the plate 16 until released by roller 28 completing its travel on the cam 27 and it is again in direct contact with the rim 9 and allowing the hinged plate 35 to drop to its normal position by its own weight. As the hinged plate 35 is forced upward the drive rod 36 which is positioned in the hole 37 in corner plate 16 and has slideable contact with the hinged plate 35 is also forced upward and likewise returns to its normal seat by its own weight when released. On reverse drive of the rim 9 by the motor 14 should the engagement of the cam 27 cramp the roller 28 and buckle the fulcrum arm 29 the hinge 38 and spring 39 will compensate until the roller 28 is under smooth travel on the cam 27. A pin 40 inserted through the hole 41 in plate 16 and seated in the hole 41a in 25 when cam 27 has forced fulcrum arm 29 to extent of its travel will hold fulcrum arm 29 against return by spring 31 and until pin 40 is removed from holes 41 and 41a the swiveled fulcrum drive device 25 will not operate, allowing full power of the motor 14 to be exerted on the driving rim 9. When the hinged plate 35 is forced upward by the roller 33 the insulated arm 42 engages with the spring contactor 43 seating it against the spring contactor plate 44 providing in-

65 intermittent electrical connection between 20b and 21a.

The electric control panel 19 is mounted on the corner plate 16a on the studs 45 and held by the thumb nuts 46 which automatically make electrical connections when seated to the terminal holes 48. Panel is mounted with a double knife main switch 47 which is electrically connected to the terminal holes 48b, 48c and 48d, a single knife auxiliary switch 49 which is electrically connected to the terminal holes 48b and 48d, a push button 50 which is electrically connected to terminal holes 48a and 48d for control through contact track 51, and a push button 62 which is electrically connected to terminal holes 48b and 48d for control through corner plates 16. The terminal hole 48 provides for a panel connection to the positive side 52 of the transformer 53 if desired.

The electric circuits as employed in unit A are as follows: From plus 52 on transformer 53 to control panel stud 45 to center pipe 5 which is electrically contacted to rim 9 and therefore any device attached to 9 is electrically connected to transformer plus 52 and another contact made from 5 to center boss terminal stud 56 provides transformer plus 52 connection for any device attached to terminal stud 56. Control panel stud 45 also connected to 17b in 1b at 16 to provide transformer plus 52 connection for devices attached to corner plates 16. Transformer minus 54 connected to control panel stud 45d. A connection from control panel stud 45a taken through hollow of pipe 5 with slip on terminal 61a for attachment to center boss terminal stud 56a which is connected also to the inside contact track 51. A connection from control panel stud 45b taken through hollow of pipe 5 with slip on terminal 61b for attachment to center boss terminal stud 56b and another connection is made from 45b to terminal studs 17 in 1b at 16. A connection from control panel stud 45c taken through hollow of pipe 5 with slip on terminal 61c for attachment to center boss terminal stud 56c and another connection is made from 45c to the outside contact track 55. A connection is taken from terminal studs 17a in 1b at 16 through the hollow of pipe 5 with slip on terminal 61 for attachment to center boss terminal stud 57 to provide intermittent contact for devices operated in connection with center boss terminals by the action of the corner plate device 16. Other means of intermittent contact for devices operated in connection with center boss terminals is provided by the contact roller 60 engaging with the ramp 59 on rim 9, contact roller 60 being attached to top 1d and electrically connected to the center boss terminal 58.

The double knife main switch 47 on control panel 19 controls all circuits when closed. The single knife auxiliary switch 49 controls

the independent circuit leading to the corner plates 16. The push button 50 controls the independent circuit leading to the inside contact track 51 and the push button 62 controls the independent circuit leading to the outside contact track 55.

Unit B, comprising vehicles, moving objects and the like, with and without electrical contactors to tracks 51 and 55 and driven by the power rim 9 connection being made by a clamp 63 and thumb screw 64, the clamp 63 being suitably attached to the object to be driven by the power rim 9 and also providing means of plus 52 connection for electrical energy with the minus 54 being represented in contacts to the tracks 51 and 55.

In Figs. 11, 12, 13, 14 and 15 is shown an ordinary motored fire engine with rubber tired wheels, the clamp 63 being attached to the forward wheel truck 65 which has swivel action at 66. Another insulated clamp 63a is attached through an arm 67 to the rear end of the vehicle frame providing means to hold vehicle in driving line on the track 55. A suitable reflector box 68 is mounted under motor compartment hood and having two headlight formed openings 69 at front, an electric lamp 70 is mounted in box 68 and electrically connected to clamp 63 and metal frame of vehicle which is connected to the track 55 by the roller contactor 71. Lamp 70 is controlled by main switch 47 on control panel 19. A red bulb light 72 is mounted in hollow of engine boiler with electrical connection to clamp 63 and track 51 by the roller contactor 73 and is controlled by the push button 50 on the control panel 19 to flash red light through fire engine stack opening 74. The rear truck axle carries a gear 75 meshed with a circular floating gear 76 bearing a center pinion 77 which revolves when the rear wheel bearing the gear 75 is driven furnishing a means of power upon and within the vehicle when it is driven by the rim 9 and in this instance providing means for an intermittent electrical contact by the contact arm 78 on the pinion 77 engaging with the wiping contactor 79 as the vehicle is driven, the gong 80 being connected electrically to the wiping contactor 79 and clamp 63 it is intermittently sounded when the vehicle is driven by the rim 9 and is controlled by the main switch 47 on control panel 19, as the wiping contactor device furnishes a ground connection through vehicle frame and its track 55 contactor 71.

In Figs. 16, 17, 18, and 19 is shown an ordinary racing automobile with rubber tired wheels which engage on one side with the track 51 and on the opposite side with the track 55 the vehicle straddling and driven by the rim 9 by attaching thereto with the clamps 63 and 63a and thumb screws 64 and 64a suitably mounted on the vehicle wheel trucks which swivel at 81 with means of peripheral alinement by the set screw 82. Intermittent

electric contact breaker and means for power within and upon the vehicle are provided in the device 83 attached to the side frame of the vehicle and having a grooved contact 5 wheel 84 engaging with the track 55 and rotating thereupon when vehicle is driven, the wheel 84 bears an eccentric pinion 85 which intermittently engages with the contact wiper 86 and a double pulley 87 for 10 power purposes upon the vehicle (not shown) which is driven by the belt 88 working in the groove of contact wheel 84. The electric light 89 with red glass 90 located in rear end of vehicle is electrically connected to the 15 contact wiper 86 and the power rim clamp 63 giving it intermittent action and under control of the main switch 47 on control panel 19 through rim 9 and track 55.

In Figs. 20, 21, 22 and 23 is shown a vehicle 20 with metal wheels which engage with the track 55 and driven by the rim 9 by attachment thereto with a single clamp 63 and thumb screw 64 which is attached to the side section of the vehicle by an arm 91. The light 25 70 and the gong 92 duplicates description, action and control as given previously under fire engine Figs. 11, 12, 13, 14 and 15, the gong taking the place of the fire engine light 72 and is sounded by pressing of the push button 50 on control panel 19.

In Figs. 24, 25 and 26 is shown a wheel mounted object with an eccentric rear axle 93 for hopping motion when object is driven by the rim 9, it being attached thereto by the 30 clamp 63 and thumb screw 64 attached to the offset arm 94 which has swivel connection 95 to the front axle, the wheeled object traveling upon the track 55.

In Figs. 27, 28 and 29 is shown a double 40 trucked wheeled vehicle to travel in the grooves 96 of track 55 or upon raised tracks (not shown) the trucks 97 swiveling at 98. The trucks 97 are attached to driving rim 9 by insulated arms 99 carrying clamp 63 45 and thumb screw 64.

In Figs. 30, 31, 32 and 33 is shown a single trucked wheeled vehicle to travel in the grooves 96 of the track 55 or upon raised tracks (not shown). The light 100 mounted 50 in the vehicle is electrically connected to the clamp 63 and grounded to frame of vehicle which having contact with track 55 is controlled by the main switch 47 on control panel 19.

In Figs. 34, 35, 36, 37 and 38 is shown a single trucked locomotive to travel in the grooves 96 of track 55 or upon raised tracks (not shown). The light mounted as a headlight in the front crown of the vehicle is electrically connected to the clamp 63 and grounded through frame of vehicle which having contact with track 55 is controlled 60 by the main switch 47 on control panel 19. The bell signal 101 is rockably mounted 102 65 to the rear crown of the vehicle and has a

slotted rocker arm 103 engaging with an offset driving rod 104 terminating in a magnet draw bar 105 of the solenoid 106. The solenoid 106 being electrically connected to clamp 63 and contact roller 73 which engages with track 51 is under control of the push button 50 on the control panel 19 and the bell 101 is therefore rung at remote control as represented in operation of the solenoid 106 on the draw bar 105 to rock the bell 101.

In Figs. 39, 40, and 41 is shown a vehicle 75 boat to be run on floor of aquatic tank 11 by means of the driving arm 107 which is designed to clear the rim of the tank 11 and attached to the driving rim 9 by the clamp 63 and thumb screw 64 and connected to the vehicle by insertion into the slotted member 108 mounted to the extension of the fixed axle 109. Eccentric mounted contact roller 110 on the vehicle wheel 111 engages with the wiping contact 112 when the vehicle is driven by the power rim 9. The light 113 is electrically connected to the wiping contact 112 and intermittently connected to the track 55 contact roller 71 when completed by contact roller 110 on the vehicle wheel 111 engaging with the wiping contact 112 and the other side of the light 113 being electrically connected to the rim clamp 63 it is controlled with intermittent action by main switch 47 on the remote control panel 19, or the push button 50 on control panel 19 by the dual ground connection through contact roller 73 and track 51 as shown in Fig. 41.

In Figs. 42, 43, 44, 45, 46 and 47 is shown an air beacon or revolving light lighthouse to be mounted centered over boss 10 by a plate 116 thumbscrewed to the boss terminal studs 56, the plate 116 being attached to a base 117 center drilled for a shaft box 123 to receive a shaft 118 which is center mounted in the light tower 119 which bears at its top a light 120 half shaded with a reflector 121. Mounted on the top of the base 117 is a four way contactor 122 which intermittently engages with the contact wipers 124 when the driving arm 125 attached to the tower 119 and to the driving rim 9 by the clamp 63 and thumb screw 64 is rotated by the rim 9 as driven by the motor 14 and the light 120 being electrically connected through the contact wipers 124 and 124a and contact plate 122 to the track contactor 71 engaging with the track 55 and to the rim 9 through the driving arm 125 a 110 flashing light is obtained at relatively the four points of a compass, the shaded reflector 121, the four way contact 122 and the contact wipers 124 and 124a being synchronized to obtain that result, the light 120 being under control of the main switch 47 on the remote control panel 19.

In Figs. 48, 49 and 50 is shown a buoy 115 designed to float in water of aquatic tank 11, the float 126 bearing a standard 127 with a light 128 which is electrically connected 120

through flexible cable 129 to terminals 130 and 130a on attaching plate 131 having a tank 11 inner rim clamp 132 and thumb screw 133. Terminal 130 electrically connected to

the invention into effect, and the invention is therefore claimed broadly in any of its possible forms or modifications within the scope of the appended claims.

Having thus described my invention I 70 claim:

1. In an amusement device, the combination of a power driven disc, a housing having an opening in the top thereof, a rim associated with said disc extending upward through and above said opening, tracks on each side of the opening, contact plates for said tracks, a remote control panel, means for electrical connection between the panel and the aforesaid rim, and plural control means on the panel.

2. In an amusement device, the combination of a power driven disc, a disc housing, the top of the disc housing having an annular opening, an annular rim extending upward through and above said opening and associated with the power driven disc, tracks adjacent the opening, objects adapted to be driven mounted in the center of the housing top, a driving connection between the rim and said objects, and a frame for supporting the housing top.

objects, means for electrical connection and control of the objects through the rim and the track, an attaching foot through which the electrical connection is effected, a remote control panel, a hollow rim pivot with which a further connection is made through the hollow rim pivot to the remote control panel, a source of electrical energy, an intermediate rim contactor, a make and break contactor, means of connection through the aforesaid contactors, a subdriving device by which the make and break contactor is primarily operated, cams on the rim with which the subdriving device is in contact, the above-mentioned driven objects carrying means within 105 same for intermittent electrical contact. 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360

115 through the aforesaid cams, the housing having a corner section, a lift mounted in said corner section, objects or devices mounted on said sections and adapted to be operated, a remote panel, means for electrical connection and control of said objects from the remote panel through the rim and the fulcrum device to the lift, a terminal mounted on the top of the section, other terminals mounted on the top of the section in direct connection with the remote panel, a separate circuit, a make and break spring contactor through which the separate circuit leads, said make and break spring contactor being actuated by the lift, corner section tops, objects on said corner section tops arranged for electrical control, the said corner section tops being mechanical- 120 125 130

20 to 56c as shown in drawings places light 128 under control of push button 50 on control panel 19. Connection of 130a to 56b gives choice of light 128 control to push button 62 or auxiliary switch 49, a total choice of four single controls or four collective controls by plural connection from 130a to 56a, 56b, and 56c, and from 130 to 56.

25 In Figs. 51, 52 and 53 is shown a lighthouse designed to be mounted on the inner rim of tank 11 by a slip on base 135 with a tower 136 on which is mounted a top beacon light 137 and a fog gong 138, the light 137 being electrically connected to boss terminal studs 525

30 trically connected to boss terminal studs 56b and 58 and the gong electrically connected to boss terminal studs 56b and 57 placing both under control of the main switch 47 on the control panel 19. The light 127 being inter-

35 control panel 19. The light 137 being intermittently operated by its circuit leading through the corner plate 16 device with its breaker contactor 43-44 and the gong being sounded intermittently by its circuit leading through the device 16.

40 through contactor 60 engaging with the ramp 59 on driving rim 9, both being governed by the drive of the rim 9 by the motor 14, acting in consequence on the contact of rim ramp 59 on roller contactor 60 and the hinged plate 35 on corner plate 16 through the fulcrum

45 Unit D, comprising objects to be floated in the air with mechanical drive and electrical contacts as described in introductory paragraph of unit B.

50 From the above description it will be apparent that there is thus provided a device of the character described, possessing the particular features of advantage before enumerated as desirable but which obviously is sus-

ceptible of modification in its form, proportion, detail construction or arrangement of parts, without departing from the principle involved or sacrificing any of its advantages.

60 While in order to comply with the statute, the invention has been described in language more or less specific as to certain structural features, it is to be understood that the invention is not limited to any specific details, 65 but that the means and construction herein described comprise but one mode of putting

ly operated by the lift through the fulcrum drive connection with the power driven disc rim.

4. In an amusement device, the combination of a power disc, a housing having an annular opening in its top, an annular rim extending upwardly through said opening and driven by the power disc, contact plates adjacent the opening, a vehicle or object adapted to be propelled, means for attaching and detaching said element to the rim for propulsion along the outer contact plate, a headlight on the vehicle, electrical connections from the rim and the contact plates to operate the headlight, a shaded light within the vehicle, an intermittently sounded gong within or upon the vehicle, a remote panel, means for controlling the aforesaid lights from the panel, and reflex power means within the vehicle produced through the drive of its rear wheels.

5. In an amusement device, the combination of a power disc, a housing having an annular opening through its top, an annular upturned rim associated with the power disc and extending through said opening, contact plates adjacent the opening, a vehicle to be propelled, the rim having a slot, means for attaching the vehicle astride the slotted rim and wheeled upon both contact plates, contact breaker means within the vehicle, an independent track contact wheel to break the circuit, and means to hold the vehicle in line with the rim as wheeled upon the contact plates.

6. In an amusement device, the combination of a power disc, a housing top having an annular opening in same, a rim actuated by the power disc and extending upwardly through said opening, a wheeled object, means for attaching said wheeled object to the extended rim to travel on the top of the housing adjacent the rim, an object to be propelled, and means on said object arranged to obtain an eccentric action of the object while in motion.

7. In an amusement device, the combination of a power disc, a disc housing having an opening in the top thereof, an upturned rim actuated by the power disc and extending through said opening, tracks adjacent the opening, means for attaching the wheeled vehicle to the rim and holding it in line therewith and upon the tracks thereto, means within the vehicle for illuminating same and electrical connections from said illuminating means through the track and the rim, and a remote control panel electrically connected therewith.

8. In an amusement device, the combination of a power disc, a disc housing having an annular opening in the top thereof, an annular rim actuated by the power disc and extending upwardly through said opening, circular tracks adjacent the opening, means for attaching a wheeled vehicle to the rim, means

of illumination upon the vehicle, electrical connections from said illumination means to the track and rim, a sound signal within the vehicle, means within the vehicle for operation of said sound signal, and a remote panel having electrical connection with the aforesaid mechanism.

9. In an amusement device, the combination of a housing, a floor for the housing, a central hollow pivot for the floor, a centering boss, encircling said pivot, a power disc, power operated means for driving said power disc, leveling bearings on which the power disc is mounted, a driven disc carried by the power disc, an annular slot in the housing, an annular rim on the driven disc said rim extending vertically through the aforesaid annular slot, the aforesaid slot separating the housing into an inner and an outer part, the outer part being secured to the housing, and the inner part constituting a disc, leveling bearings engaging opposite sides of the driven disc, and a toy element attached to the vertical rim of the driven disc and actuated thereby.

10. In an amusement device, the combination of a housing, a floor for the housing, a central pivot for the floor, a power disc, a driving wheel belted to the power disc, leveling bearings on which the power disc is mounted, a driven disc carried by the power disc, an annular slot in the housing, an annular rim on the driven disc said rim extending vertically through the aforesaid annular slot, said slot separating the housing into an inner part and an outer part, the outer part being affixed to the housing, the inner part constituting a stationary disc, leveling bearings engaging opposite sides of the driven disc, and a toy element attached to the vertical rim of the driven disc and actuated thereby.

11. In an amusement device, the combination of a housing, a floor for the housing, a central pivot affixed to the floor, a power disc rotatably mounted on said pivot, power operated means operatively connected to and driving said power disc, a driven disc carried by the power disc, an annular slot in the housing, an annular rim on the driven disc said rim extending vertically through the said annular slot, the said slot separating the housing into an inner part and an outer part, the outer part being secured to the housing, and the inner part constituting a disc, leveling bearings engaging opposite sides of the driven disc, an aquatic tank mounted on the inner part, and an aquatic toy element positioned in said tank and operatively attached to the rim of the driven disc.

12. In an amusement device, the combination of a power driven disc, a hollow center pivot on which the disc is mounted, a housing within which the power driven disc

is enclosed, the top of the housing having a continuous opening therein, a rim on the power driven disc extending through and above the aforesaid continuous opening in 5 the housing top, the housing having continuous tracks, contact plates and vehicles adapted to travel on the said tracks, the vehicles being attached to and driven by the aforesaid rim, and power means for rotating 10 the aforesaid power driven disc.

13. In combination with the apparatus defined in claim 12, electrical devices in the vehicles arranged for intermittent operation as the power disc is rotated to simulate 15 signals.

14. In an amusement device of the type described, the combination of a power driven disc, a disc housing top having an annular opening therein, an annular rim extending 20 upward through and above said opening, an aquatic tank located on the portion of the housing top within said annular opening, toy elements within the tank adapted to be driven, a driving connection between the rim 25 and said objects, power means for actuating the power driven disc and thereby causing the elements in the tank to be set in motion.

15. In an amusement device of the type 30 described, the combination of a housing, the top of the housing having an annular slot, a driven disc within the housing said disc having an annular vertical rim extending through the slot in the housing top, an aquatic 35 tank mounted on the part of the housing top within the annular slot, toy elements to float in the aquatic tank, means connecting said toy elements with the rim of the driven disc for operating the toy elements, signal 40 devices mounted in the center of the housing top and controlled by the operation of the driven disc.

16. In combination with the apparatus 45 defined in claim 15, signals mounted on corner sections of the outer portion of the housing top, a fulcrum drive for said signals, cams affixed to the periphery of the driven disc to contact with the fulcrum drive, a hinged lid, a driving rod on which said hinge 50 lid acts, a remote control panel, and electrical means for energizing said signals from the remote control panel.

In testimony whereof I affix my signature.
WAYNE P. ZENT.
